UNITED STATES PATENT OFFICE

JOSEPH BETHENOD, OF PARIS, FRANCE

HIGH-POWER THERMIONIC TUBE

Application filed December 28, 1923, Serial No. 683,101, and in France January 11, 1923.

In my U. S. patent application, Serial No. 642,946 for "high power electron generating device" filed June 2, 1923, especially when the frequency of the current producing the heating in the cathode is relatively high, provisions have been made so that the magnetic circuit may be incompletely closed. The object of the present application mainly is to outline and indicate certain arrangements that are of advantage in this respect. As shown in the drawing herewith by way of example, cathode 2 has the form of a circular plate (disk) the cross-section of which along a generatrix may, however, be made of any desired cross-sectional shape at all. This cathode is heated by the aid of the flux emanating from core 5 excited by winding 6 through which is passed a current of sufficiently high frequency. The grid which is likewise of circular shape, is shown at 4. The anode 3 finally is here supposed to be constituted by the bottom of a cylinder, and it forms jointly with a piece 1 made of a convenient insulating material (glass, quartz, etc.) an envelope or bulb wherein a vacuum is established. It is to be noted that the joint between 1 and 3 is insured in a way as may be convenient to suppress all leakage. The whole thus constructed could be disposed in a vat 7 in which a chilling agent, such as oil, etc., could be circulated. Such cooling could be confined, however, to anode 3, which in this case must be constructed with a double bottom.

At all events, the form and the constitution of the electrodes are arbitrary; in particular, anode 3 and cathode 2 may be given, if so desired, either both or only one of them, the form of concave or convex mirrors, of cones or of truncated cones, etc., with this particular end in view of distributing as advantageously as feasible the electron emission from the cathode.

It is furthermore nearly always of advantage to choose the thickness of cathode 2 and the frequency of the heating current in such a way that the alternating magnetic flux emanating from 5 will not attain the grid 4 and the anode 3, etc.

Vat 7, moreover, made of red copper, for

instance, could be built so as to form a screen and serve to limit the space inside which the flux in question may circulate.

Finally, in certain cases, especially where the grid 4 is done away with, one could utilize the flux passing through cathode 2 for the production in known manner a periodical interruption of the current circulating between 3 and 2; a ring 8 built up of laminated sheets of magnetic material could then be used to advantage for the purpose of guiding the said flux. In other words, the presence of ring 8 will attract or deflect the magnetic field emanating from core 5 for heating cathode 2 and thus prevent said magnetic field from reaching the grid and anode electrodes. However, this ring may be found useful under all circumstances and forms of arrangements.

Having described my invention, what I claim is:

1. In a thermionic device, a cathode having a relatively large disk-like surface, means for heating said cathode by induction comprising a magnetic core and an induction coil for energizing said core, and a magnetic annular member for influencing the path of the flux emanating from said magnetic core.

2. In a high power thermionic tube, an anode and a cathode having relatively large disk-like surfaces disposed within an evacuated envelope for obtaining an increased electron emission therebetween, means for inductively heating said cathode including an inductance coil and a magnetic core disposed adjacent said cathode, and means separate from the electrodes of said tube for preventing the flux emanating from said core from influencing the anode.

JOSEPH BETHENOD. 90
